UNITED STATES PATENT OFFICE.

NORRIS A. JUDD, OF SAN FRANCISCO, CALIFORNIA.

TEMPORARY BINDER.

1,235,900.

Specification of Letters Patent.

Patented Aug. 7, 1917.

Application filed January 3, 1917. Serial No. 140,448.

To all whom it may concern:

Be it known that I, NORRIS A. JUDD, a citizen of the United States, residing in the city and county of San Francisco and State 5 of California, have invented certain new and useful Improvements in Temporary Binders, of which the following is a specification.

The present invention relates to improvements in temporary binders and more particularly to that type of binder for receiving and protecting books or magazines. The invention has for its principal objects to provide a construction whereby the contents 10 thereof is locked from removal therefrom by unauthorized persons, one which may be manufactured at little cost and which will enable the book or magazine to be readily placed therein or removed therefrom by 15 operation of a simple lock controlled mechanism, without in any way mutilating or injuring the book or magazine placed therein.

With the above mentioned and other objects in view, the invention consists in the 20 novel construction and combination of parts hereinafter described, illustrated in the accompanying drawings, and set forth in the claims hereto appended; it being understood that various changes in the form, proportion, size and minor details of construction 25 within the scope of the claims may be resorted to without departing from the spirit or sacrificing any of the advantages of the invention.

30 To more fully comprehend the invention, reference is directed to the accompanying drawings, wherein,

Figure 1 is a longitudinal sectional view through the back bone of the preferred embodiment of my invention with a magazine locked from movement therein.

Fig. 2 is a view in detailed section of the movable end lock retaining member in extended or unlocked position.

45 Fig. 3, is an end view of the improved binder.

Fig. 4 is a view in detailed top plan of the movable end locking member in locked position.

50 Fig. 5 is a sectional view taken on line 5—5 of Fig. 4.

Referring more particularly to the several views of the drawings, wherein like characters of reference designate corresponding parts, 1, indicates a suitable stiff or rigid binder back bone substantially U

shaped in cross section and open at its opposite ends. To the upper side edges 1', of the back bone 1, are flexibly connected or attached as at 2, the binder cover members 3, preferably of board or other rigid or flexible material.

Positioned within the back bone 1, adjacent the opposite ends thereof, are the end members 4 and 5, each of a width approximately equal to that of the interior of the back bone 1 and including respectively the base portions 6 and 6', vertical portions 7 and 7' and the tongue or hook members 8 and 8', which project over the respective 65 base portions 6 and 6', between the upper side edges 1' of the back bone.

The end member 4, is fixed within the back bone 1, adjacent one end, by a suitable rivet or other securing means 9, and under 70 the tongue portion 8 thereof, is adapted to be received one end of a binding rod 10 which is removably positioned within a book or magazine, preferably longitudinally between the leaves thereof and extending at its 75 ends slightly beyond the ends of the book or magazine, as in Fig. 1.

The end member 5, is positioned within the back bone 1 adjacent the opposite end thereof and is formed in its base 6' with a 80 longitudinal guide slot 12, through which extends the retaining rivet or member 13, passing through the back bone of the binder, the member 13 providing a guide or retainer relatively to which the end member slides 85 longitudinally of the back bone of the binder. A flat locking spring 14 is retained in fixed position on the base portion 6' of the end member 5, by the rivet or retaining member 13, which extends through the outer end 90 thereof and when said locking member is moved to its innermost position, as in Figs. 4 and 5 of the drawings, the free end 15 of said spring 14 engages the upturned end 16 of the base 6', of the end member 5, locking 95 the same from outward movement.

The back bone 1 is provided, in one of its side walls 1', adjacent the free end of said spring 14 as in Fig. 4, with a key or pin insertion opening 17, and the edge of the 100 spring opposite said opening is raised or bowed upwardly as at 18 to guide a suitable key or pin, not shown, beneath the spring when inserted through the opening 17. The insertion of the key or pin in the opening 110 17, raises the free end of the spring above the upturned end 16 of the base 6', permit-

ting longitudinal movement of the end member 5 relative to the back bone 1, of the binder.

In positioning a book or magazine within 5 the binder, the rod 10, is first placed between the leaves of the book, preferably in the center thereof and is tightly pressed against the back thereof with the opposite ends projecting beyond the end of the book as in 10 Figs. 1 and 2 of the drawings. The end member 5 is then manually moved outwardly relative to the back bone 1 of the binder as in Fig. 2 of the drawings, by first releasing the spring 14, through the insertion 15 of a key not shown, in the opening 17. The back of the book 11, is then positioned within the back bone of the binder within one end of the binding rod 10 beneath the tongue 8 of the end member 4. The end member 5 is then moved inwardly over the 20 other end of the rod 10 as in Fig. 1 until the free end 15 of the spring 14 engages the upturned end 16 of the base 6 of the end member 5, at which time the book is locked within 25 the binder with the tongues 8 over the opposite ends of the rod 10 and to remain in such position until a key is inserted to raise the free end of the spring 15, when the end 5 may be moved outwardly and the book removed from the binder. 30

It is apparent that it is not required to mutilate the book in any manner to position the same within the binder, and the book may be positioned within or removed 35 from the binder with little effort, and when positioned within the binder, is locked from movement, by any unauthorized persons.

Having thus described my invention, what I claim is:—

40 1. A binder for books and the like, comprising a channeled back bone for receiving the back of a book, a binder rod for coöperation with a book and adapted to project beyond its ends, cover members hinged to 45 the side edges of said cover back bone, a pair of end members mounted within said channeled back bone and each including an inwardly disposed tongue portion, adapted to overlie the projecting ends of the binder rod when the book is positioned within the 50 binder, one of said end members capable of movement lineally of the channeled back bone to permit of the insertion of said binder rod between said end members, and key releasable lock controlled means for maintaining said slidible end member in position to lock said binder rod between said end members. 55

2. A binder for books and the like, comprising a channeled back bone for receiving the back of a book, a binder rod for coöperating with a book and adapted to project beyond its ends, cover members hinged

to the side edges of said back bone, a pair of end members facing each other and mounted within said channeled back bone, each of said end members comprising a base portion and a tongue portion over-hanging the same in spaced relation thereto, said tongue portions adapted to overlie the ends 65 of said binder rod when the same is positioned within the back bone of the binder, means for attaching each of said members to said back bone, one of said end members 70 slidable relatively to its attaching member 75 and longitudinally of said back bone and provided with an upturned inner end, a key released spring carried by one of said attaching members for engaging the upturned end of said slidible end member to lock the 80 same from outward movement.

3. A binder for books and the like, comprising a channeled back bone for receiving the back of a book, a binder rod for removably positioning between the leaves of a book with its ends projecting beyond the ends thereof, cover members hinged to the side walls of said channeled back bone, a pair of locking end members carried within the channel of the back bone for engaging 85 over the projecting ends of said binder rod to retain the book in position within the binder, one of said end members capable of movement from the other member to inoperative position, and key releasable means 90 for automatically locking said movable end member when the same is in said first mentioned position.

4. A binder for books and the like, the same comprising a channeled back bone for receiving the back of a book and provided with a key insertion opening in its side wall, a binder rod for removably positioning between the leaves of a book with its ends projecting beyond the ends of the book, 100 cover members hinged to the side walls of said channeled back bone, a pair of locking end members carried within the channel 105 of the back bone and adapted when in operative position to project over the opposite ends of said binder rod to retain the book in position within the binder, one of said locking end members capable of movement longitudinally of the binder back bone to inoperative position, and means releasable 110 through said opening in said back bone side wall for locking said movable end member 115 in its operative position.

In testimony whereof I have signed my name to this specification in the presence of 120 two subscribing witnesses.

NORRIS A. JUDD.
